DESIGN FOR A PROPHYLACTIC DEVICE FOR THE ORAL CAVITY

Edwin I. Brothers and Abe R. Brothers, Brooklyn,
N. Y.

Application October 19, 1935, Serial No. 59,138

Term of patent 14 years

To all whom it may concern:

Be it known that we, Edwin I. Brothers and Abe R. Brothers, citizens of the United States, residing at Brooklyn, in the county of Kings and State of New York, have invented a new, original, and ornamental Design for a Prophylactic Device for the Oral Cavity, of which the following is a specification, reference being had to the accompanying drawing, forming part thereof.

Figure 1 is an underneath plan view of a

prophylactic device for the oral cavity showing our new design.

Figure 2 is an elevational view thereof.

Figure 3 is a cross-sectional view taken on the line 3—3 of Figure 1.

We claim:

The ornamental design for a prophylactic device for the oral cavity, as shown.

EDWIN I. BROTHERS.
